UNITED STATES PATENT OFFICE.

CHARLES H. TREAT AND ANDREW B. BANGHART, OF GEORGETOWN, DEL.

DESIGN FOR A DISH.

SPECIFICATION forming part of Design No. 17,035, dated December 21, 1886.

Application filed April 2, 1886. Serial No. 192,312. Term of patent 7 years.

To all whom it may concern:

Be it known that we, CHARLES H. TREAT and ANDREW B. BANGHART, both citizens of the United States, and residents of Georgetown, Delaware, have invented a certain new and original Design for Dishes, of which the following is a specification, reference being had to the accompanying drawings, forming part thereof.

- 10 Figure 1 is a plan view of our newly-designed dish. Fig. 2 is an edge view of the same, and Fig. 3 is a cross-sectional view taken on the line *e f* of Fig. 1, these three views being deemed necessary to fully illustrate our design.
- 15 The leading feature of our design consists in the four corners, concave on their inner surface and convex on their outer surface, and the four equal sides having a slightly-dishing convex form inwardly.
- 20 The corners in our design are concave on the inner surface and convex on the outer surface in form as stated, and project out beyond the lines of the sides.
- 25 A is the bottom in the dish, and *b b* are the four equal sides, which join the bottom *A* along the curved lines *d d*. These sides *b b* are slightly convex inwardly in a dishing form where they join the bottom, but are approximately straight

along their upper edges. The sides *b b* merge into the outwardly-convex corners *c c*, as represented in the several figures, thus presenting to the eye the combined effect (when viewed as in Fig. 1) of an outline of four equal straight sides and four convex and projecting corners, the bottom of the dish having the four equal 35 and inwardly-curved lines and four equal and outwardly-curved corners. The upper edges of the dish are straight along the sides until they reach the corners, and then curve first downward and then upward to the extremity 40 of the corners, as shown in Figs. 2 and 3, thus giving to the design a pleasing diversity of outline.

We claim—

The design for a dish herein described and shown, the same consisting of a dish having a plain bottom, *A*, four equal inwardly-convex dishing sides, *b b*, merging into the bottom *A* upon the curved lines *d d*, and the four inwardly-concave projecting corners *c c*.

CHAS. H. TREAT.
ANDREW B. BANGHART.
